CLAIM

The ornamental design for a combination cigar lighter and cutter, as shown and described.

DESCRIPTION

FIG. 1 is a perspective view of a combination cigar lighter and cutter showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a front elevational view showing our combination cigar lighter and cutter in its cutting mode; and,

FIG. 9 is a perspective view showing our combination cigar lighter and cutter in its lighting mode.
